UNITED STATES PATENT OFFICE

CHARLES EVERETT BILLS, OF EVANSVILLE, INDIANA, ASSIGNOR TO MEAD JOHNSON & COMPANY, OF EVANSVILLE, INDIANA, A CORPORATION OF INDIANA

METHOD OF IRRADIATION

No Drawing. Original application filed June 10, 1929, Serial No. 369,556. Divided and this application filed March 24, 1930. Serial No. 438,627.

This invention relates to a method of irradiation, particularly adapted for irradiation of fluids and substances carried in solution. The present application is a division of my 5 co-pending application, Serial 369,556, filed June 10, 1929.

The main object of the invention is to devise a method by the use of which the matter to be irradiated may be efficiently treated 10 with light rays, without exposure to the air.

The method has been used to advantage in the irradiation of solutions of ergosterol in arachis (peanut) oil, but obviously other edible oils, preferably bland vegetable oils, or 15 other solvents may be used; and the invention is equally useful for irradiating oils and other fluids not containing added ergosterol.

It is old in the art to provide irradiating 20 apparatus such as a quartz mercury vapor lamp and to locate the same in any desired position relative to a receptacle containing the substance to be treated. In using such apparatus, the relative positions of the lamp and the receptacles are not always arranged 25 to the best advantage for the intended purpose, and the treated substance may be exposed to air, which is to be avoided, especially in the case of oils which become rancid when exposed to ultraviolet light and air.

One example of a type of lamp heretofore 30 used for ultra-violet irradiation is that known as the Kromayer lamp, made by the Hanovia Chemical and Manufacturing Company, which consists of a quartz burner containing the mercury and electrodes, a quartz jacket surrounding the burner but spaced 35 therefrom to provide a vacuum chamber between the burner and the jacket, and an outer casing of metal, having inlet and outlet ports. This outer casing is spaced from the 40 quartz jacket and thus provides a chamber or passageway for water which is circulated through the chamber for cooling the burner. Of course, the water does not touch the 45 burner because it is separated therefrom by the quartz jacket and vacuum chamber. Heretofore such lamps have been placed in any desired position relative to a receptacle containing the substance to be irradiated, and 50 the light rays from the burner pass through

the quartz jacket, through the water used for cooling the lamp, and then through a window in the metal housing to the matter being treated.

A lamp of the type described may be 55 somewhat modified for use in practicing the method of the present invention. The ergosterol solution or other fluid to be irradiated may be conducted to and from the lamp in such manner that it flows through the lamp 60 chamber between the quartz jacket of the burner and the lamp casing. In this way, the material receives the full benefit of the ultra-violet light from the quartz burner without exposure to air, and the necessity for 65 water cooling the lamp is also avoided.

The preferred apparatus for use in practicing the method of this invention is fully 70 set forth, described and claimed in my said co-pending application of which this is a 75 division. Obviously, various forms of apparatus may be used. Broadly, the apparatus embodies a container for the fluid to be treated, a source of ultra violet light such as a quartz mercury vapor lamp having a chamber 80 between the quartz-jacketed burner and the lamp casing, means for repeatedly conducting the fluid from the container through the lamp chamber to expose the moving stream of fluid to the light, means for conducting the stream back to the container, and means in the system for cooling the fluid after 85 exposure to the light. Preferably the container for the fluid is provided with inert gas to occupy the space above the level of the fluid in the container. A pump or other suitable means may be provided for circulating the fluid.

The method consists in placing the fluid or substance in solution, to be irradiated, 90 in a container, causing a stream of the fluid to be circulated, in a practical absence of air, exposing successive parts of the moving stream to light rays, cooling the exposed parts of the stream, and repeating the cycle of operations until irradiation is complete.

The circulation of the oil solution is continued as long as is necessary to obtain good activation. For example, to activate two liters of a solution of ergosterol consisting of 100

ten grams of ergosterol in two liters of arachis oil, using a modified Kromayer lamp at normal voltage, requires about three hours. However, the time of activation depends on many factors, such as voltage, age and condition of the lamp, concentration of the ergosterol solution, rate of circulation through the lamp, purity of the solvent, etc.

From the foregoing it will be seen that the oil being circulated is at no time exposed to the deleterious effects of the air; all the fluid is uniformly treated with the light rays, and the full radiance of the lamp is utilized for its intended purpose. The circulation of the oily fluid through the lamp, as herein described, therefore results in unusually efficient and direct irradiation and obviates the necessity for water cooling the lamp.

I claim:—

- 20 1. The method of irradiating fluids and substances in solution, which consists in causing a stream of the fluid to be circulated, exposing successive parts of the moving stream to ultra-violet light, cooling the exposed parts of the stream, and repeating the cycle of operations until the irradiation is complete.
- 25 2. The method of irradiating fluids and substances in solution, which consists in causing a stream of the fluid to be circulated in a practical absence of air, exposing successive parts of the moving stream to ultra-violet light, cooling the exposed parts of the stream, and repeating the cycle of operations until the irradiation is complete.
- 30 3. The method of irradiating fluids and substances in solution, which consists in causing a stream of the fluid to be continually circulated, exposing successive parts of the moving stream to ultra violet light by passing the stream into direct contact with a source of ultra violet light, cooling the exposed parts of the stream after the same have passed out of contact with the source of light, and repeating the cycle of operations until the irradiation is complete.
- 35 4. The method of irradiating fluids and substances in solution, which consists in causing a stream of the fluid to be continually circulated in a practical absence of air, exposing successive parts of the moving stream to ultra violet light, by passing the moving stream into the space between the casing and the quartz jacket of the burner of a quartz mercury vapor lamp, cooling the exposed parts of the stream after same have passed out of said lamp, and repeating the cycle of operations until the irradiation is complete.

In testimony that I claim the foregoing as my invention, I affix my signature this 20th day of March, 1930.

CHARLES EVERETT BILLS.
